CRACKING HYDROCARBON OILS

Joseph Mason Barron, Port Arthur, Tex., assignor
to The Texas Company, New York, N. Y., a cor-
poration of Delaware

Application November 18, 1942, Serial No. 465,949

4 Claims. (Cl. 196—49)

This invention relates to a combination catalytic cracking and thermal cracking process for the production of a maximum yield of high anti-knock gasoline or motor fuel.

The invention contemplates a method of processing charging stocks, such as crude petroleum or topped or reduced crude, in a unitary operation in which certain fractions are subjected to catalytic cracking, certain fractions are subjected to thermal cracking and residual products of the thermal cracking are subjected to flash distillation or coking. In accordance with the invention the hot products from the catalytic cracking step are combined with vapors from the coking step in a dephlegmating zone into which charging stock is introduced to thereby accomplish fractionation of the charging stock together with products from the coking and catalytic cracking operations. The higher boiling fractions separated out in the dephlegmating zone are combined with the hot effluent from a heating zone of the thermal cracking step and the combined products subjected to pressure cracking and separated into vapors and residue. The separated vapors are fractionated to obtain higher boiling fractions, intermediate boiling fractions and lower boiling fractions. The higher boiling fractions are cycled to the heating zone of the thermal cracking step and the intermediate boiling fractions are directed to the catalytic cracking step. The vapors from the catalytic cracking and coking steps, which remain uncondensed after the dephlegmation with the charging stock, are condensed to obtain a distillate which is directed to the fractionating zone of the thermal cracking operation or are subjected to further fractionation to obtain selected fractions some of which are passed to the heating zone of the thermal cracking step and others of which are directed to the fractionator of the thermal cracking step.

For the purpose of more fully disclosing the invention reference is had to the accompanying drawing which is a flow diagram illustrative of the invention.

In the thermal cracking step hydrocarbon oil is subjected to a cracking temperature in a heating coil 10 disposed in a furnace 11. The heated products pass through a transfer line 12 to a reaction chamber 13. The reaction chamber is insulated to reduce radiation losses and the hydrocarbons therein are subjected to cracking temperature under superatmospheric pressure while simultaneously being separated into vapors and liquid residue. The separated vapors pass through a vapor line 14 to a fractionator 15

which is formed with a primary fractionating section 15A and a secondary fractionating section 15B separated by a trap-out tray 16. Each of the fractionating sections 15A and 15B are provided with suitable vapor-liquid contact elements, preferably disc and doughnut trays in 15A and bubble trays in 15B, and with suitable cooling and refluxing means for the purpose of obtaining the degree of fractionation desired. Higher boiling reflux condensate is withdrawn from the fractionating section 15A by a pump 17 by which the condensate is cycled through a line 18 to the heating coil 10. The intermediate fraction collected in tray 16 is directed to the catalytic cracking step as is hereinafter described. Vapors uncondensed in the fractionating section 15B pass to a condenser 19 thence to a distillate drum or gas separator 20.

Residual constituents from the thermal cracking operation pass through a line 21 and pressure-reducing valve 22 to a coking drum 23 wherein the residual constituents are converted to coke by means of contained heat. In practice a plurality of coking drums are employed to enable the removal of the coke without disturbing the continuity of the complete process. The vapors produced in the coking operation pass through a vapor line 24 to a fractionator 25. The fractionator 25 is preferably formed with a primary section 25A and a secondary section 25B separated by a trap-out tray 26 and the coke still vapors are preferably subjected to a primary dephlegmation in section 25A in order to separate out from the vapors the very heavy constituents which are extremely valuable as fuel oil, the heavy tarry condensate formed being removed through a line 27.

In an alternative operation, when it is not desired to reduce the thermally cracked residue to coke, the residue withdrawn through line 21 may be directed through a by-pass line 28 and passed directly to section 25A wherein the residue is flashed, the flashed residue being withdrawn through line 21.

The vapors from the coking or flashing operation which are uncondensed in the dephlegmator 25A pass to the dephlegmating section 25B into which charging stock, such as crude petroleum or topped or reduced crude, is introduced by a pump 29 and line 30. In the dephlegmating section 25B the vapors from the coking or flashing operation together with products from the catalytic cracking operation, as is explained hereinafter, are dephlegmated with the charging stock to accomplish reflux condensation of vapors and vaporization of constituents of the charging

stock. The higher boiling fractions collected on the tray 26 are withdrawn by a pump 31 and directed through a line 32 to the transfer line 12 or to the reaction chamber 13 so as to combine these fractions with the effluent from the heating coil 10 for thermal cracking in the reaction chamber.

In the catalytic cracking step intermediate reflux condensate collected on the tray 16 of the fractionator 15 is withdrawn through a line 33 and directed by a pump 34 to a heating coil 35 disposed in a furnace 36 wherein the oil is raised to the desired temperature for the catalytic cracking. The heated stream passes from the heating coil through a line 37 to a reaction chamber 38 wherein the stream is contacted with a suitable catalyst adapted to promote conversion into lower boiling hydrocarbons. In practice a plurality of catalytic reaction chambers are used so as to provide for the reactivation or regeneration of the catalyst without disturbing the continuity of the complete process.

The catalyst consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucil may be employed. Various metals such as uranium, molybdenum, manganese, lead, zinc, zirconium, nickel and the like, may be substituted in the clays or zeolites. Likewise, the combination of certain acid-treated active clays of the character of Filtral, together with added proportions of alumina or silica or both may be employed. Alumina alone may be used under certain conditions. The synthetic alumina catalysts can be improved by the addition of other constituents such as zirconium oxide or molybdenum oxide.

The hot effluent from the catalytic cracking step is directed through a line 39 to the dephlegmating section 25B wherein the hot catalytically cracked products are combined with the dephlegmated coke still vapors and serve to aid in accomplishing the vaporization of the charging stock introduced through line 30.

The vapors uncondensed in the dephlegmating zone 25B pass through a vapor line 40 to a condenser 41 thence to a distillate drum or gas separator 42. The distillate is either withdrawn from the system through a line 43 or is directed by a pump 44 through a line 45 to the fractionator 15, being either delivered through branch-line 46 to the fractionating section 15A or through branch-line 47 to the fractionating section 15B.

In an alternative operation when it is desired to segregate a particular cut for direct passage to the thermal cracking zone the vapors leaving the dephlegmator 25B may be subjected to additional fractionation. For this purpose the vapors flowing through line 40 are diverted through a line 48 to a fractionator 49. The vapors are subjected to fractionation in fractionator 49 to separate higher boiling reflux condensate from lighter constituents. The lighter constituents are removed as a vapor through a line 50 and passed thence to the condenser coil 41 and distillate drum 42 while the higher boiling condensate is directed by a pump 51 through a line 52 to the recycling line 18 or to the heating coil 10.

In practicing the invention a light gas oil stock from the fractionator 15B, as withdrawn from tray 16, is passed through the heating coil 35

wherein it is heated sufficiently to maintain cracking temperatures of the order of 850° F.-1050° F., preferably temperatures of about 910° F.-1000° F., in the catalyst case 38 containing a catalyst such as a synthetic silica-alumina catalyst. Best results are obtained by carrying a relatively low pressure in the catalyst case such as from about 5 to 100 p. s. i.

Higher boiling reflux condensate from fractionator 15A is recycled to the heating coil 10 wherein it is subjected to cracking temperatures such as 1000° F.-1030° F. The effluent from the heating coil is combined with the bottoms from dephlegmator 25B and the mixture subjected to thermal cracking in reaction chamber 13 under superatmospheric pressure such as 200-600 p. s. i. at cracking temperatures upwards of 900° F. Separation of vapors from liquid residue occurs in the reaction chamber and the separated liquid is rapidly withdrawn to prevent the accumulation of liquid in the reaction chamber.

A portion of the vapors sufficient to accomplish autogenous coking of the residue is included with the withdrawn vapors and the mixture is flashed into the coking drum wherein a low pressure of about 5-50 p. s. i. is maintained. By withdrawing the mixture from the reaction chamber at temperatures of about 910° F.-925° F. conversion to a marketable coke by means of the contained heat is readily accomplished in the coking chamber.

The hot effluent from the catalytic cracking operation is directed to the dephlegmator 25B into which topped crude is introduced. This dephlegmator also receives the dephlegmated coke still vapors from dephlegmator 25A. The fraction which is collected on the tray 26 includes residual constituents of the crude charge and condensed constituents from the coking operation. Ordinarily only a minimum, if any, of constituents from the catalytic cracking are included in this fraction, since the bulk of the catalytically cracked products distill over to the subsequent condensing or fractionating zones.

The overhead vapors from the dephlegmator 25B, comprising a mixture of straight run constituents and constituents from the coking and catalytic cracking operations, are condensed and directed as a reflux to the tower 15. In this way straight run gas oil constituents, as well as gas oil constituents from the coking and catalytic cracking operations, are combined with the thermally cracked vapors in the tower 15 and subjected to fractionation therein with the result that the light gas oil fraction collecting in the tray 16 will include not only constituents from the thermal cracking operation but also large proportions of constituents from the coking and catalytic cracking operations as well as straight-run fractions from the topped crude. The overhead distillate from the tower 15 will include gasoline from the thermal cracking, catalytic cracking and coking operations. Ordinarily it is advantageous to reduce the pressure in the tower 15 below that obtaining in the reaction chamber 13. For example, with a pressure of 400 lbs. in the reaction chamber the pressure in the fractionator may be reduced to 150-200 lbs.

The vapors from the coke drum are given a primary dephlegmation in the dephlegmator 25A under limited conditions of cooling so as to condense out only a relatively small amount of heavy tarry condensate which may be withdrawn as a fuel-oil product.

While I have described a particular embodiment of my invention for purposes of illustration, it

should be understood that various modifications and adaptations thereof, which will be obvious to one skilled in the art, may be made within the spirit of the invention as set forth in the appended claims.

I claim:

1. In the conversion of hydrocarbon oils the process that comprises subjecting hydrocarbon oil to thermal cracking in a heating zone and a communicating reaction zone maintained under superatmospheric pressure and wherein separation of vapors from liquid residue takes place, passing resultant separated vapors to a fractionating zone wherein the vapors are subjected to fractionation to separate a higher boiling fraction from intermediate and lower boiling fractions, recycling said higher boiling fraction to said heating zone, withdrawing residual constituents from said reaction zone and subjecting them to coking in a lower pressure coking zone, directing the intermediate fraction from the aforesaid fractionating zone to a catalytic cracking zone wherein it is subjected to catalytic cracking, combining the resultant products of the catalytic cracking zone with vapors evolved in the coking zone and dephlegmating the resultant commingled vapors with a residual oil charging stock in a dephlegmating zone, withdrawing the resultant bottoms from said dephlegmating zone and combining the bottoms with the effluent from the aforesaid heating zone for thermal cracking in the communicating reaction zone, subjecting uncondensed vapors from said dephlegmating zone to condensation to produce a condensate and directing said condensate to the aforesaid fractionating zone.

2. In the conversion of hydrocarbon oils the process that comprises subjecting hydrocarbon oil to thermal cracking in a heating zone and a communicating reaction zone maintained under superatmospheric pressure and wherein separation of vapors from liquid residue takes place, passing resultant separated vapors to a fractionating zone wherein the vapors are subjected to fractionation to separate a higher boiling fraction from intermediate and lower boiling fractions, recycling said higher boiling fraction to said heating zone, passing liquid residue from said reaction zone together with a sufficient portion of vapors to accomplish coking to a lower pressure coking zone wherein autogenous coking takes place, subjecting the vapors from the coking zone to a primary dephlegmation to produce a heavy tarry condensate, passing the dephlegmated vapors to a secondary dephlegmating zone, directing intermediate fractions from the aforesaid fractionating zone to a catalytic cracking zone wherein the oil is subjected to catalytic cracking, passing the resultant products of the catalytic cracking to said secondary dephlegmating zone, introducing a residual oil charging stock to said secondary dephlegmating zone, withdrawing resultant bottoms from said secondary dephlegmating zone and combining the bottoms with the effluent from the aforesaid heating zone for thermal conversion in the communicating reaction zone, subjecting uncondensed vapors from the secondary dephlegmating zone to condensation to produce a condensate and directing the resultant condensate to the aforesaid fractionating zone.

3. In the conversion of hydrocarbon oils the process that comprises subjecting hydrocarbon oil to thermal cracking in a heating zone and a communicating reaction zone maintained under superatmospheric pressure and wherein separation of vapors from liquid residue takes place, passing resultant separated vapors to a fractionating zone wherein the vapors are subjected to fractionation to separate a higher boiling fraction from intermediate and lower boiling fractions, recycling said higher boiling fraction to said heating zone, passing liquid residue from said reaction zone together with a sufficient portion of vapors to accomplish coking to a lower pressure coking zone wherein autogenous coking takes place, subjecting the vapors from the coking zone to a primary dephlegmation to produce a heavy tarry condensate, passing the dephlegmated vapors to a secondary dephlegmating zone, directing intermediate fractions from the aforesaid fractionating zone to a catalytic cracking zone wherein the oil is subjected to catalytic cracking, passing the resultant products of the catalytic cracking to said secondary dephlegmating zone, introducing a residual oil charging stock to said secondary dephlegmating zone, withdrawing resultant bottoms from said secondary dephlegmating zone and combining the bottoms with the effluent from the aforesaid heating zone for thermal conversion in the communicating reaction zone, subjecting uncondensed vapors from said secondary dephlegmating zone to further fractionation to separate higher boiling reflux condensate from a lower boiling distillate, directing said higher boiling condensate to the aforesaid heating zone and directing the lower boiling distillate to the aforesaid fractionating zone.

4. In the conversion of hydrocarbon oils the process that comprises subjecting hydrocarbon oil to thermal cracking in a heating zone and a communicating reaction zone maintained under a superatmospheric pressure and wherein separation of vapors from liquid residue takes place, passing resultant separated vapors to a fractionating zone wherein the vapors are subjected to fractionation to separate a higher boiling fraction from intermediate and lower boiling fractions, recycling said higher boiling fraction to said heating zone, withdrawing liquid residue from said reaction zone and subjecting it to flashing to separate a residue from flashed vapors, directing intermediate fractions from said fractionating zone to a catalytic cracking zone wherein the oil is subjected to catalytic cracking, combining the resultant products of the catalytic cracking with the flashed vapors in a dephlegmating zone, introducing a residual oil charging stock to said dephlegmating zone, withdrawing the resultant bottoms from said dephlegmating zone and combining the bottoms with the effluent from the aforesaid heating zone for thermal cracking in the communicating reaction zone, subjecting uncondensed vapors from said dephlegmating zone to condensation to produce a condensate and directing said condensate to the aforesaid fractionating zone.

JOSEPH MASON BARRON.
